UNITED STATES PATENT OFFICE.

EDWARD ANDERSON, OF DAYTON, OHIO, ASSIGNOR, BY MESNE ASSIGNMENTS, TO SIMONDS WORDEN WHITE COMPANY, A CORPORATION OF OHIO.

GRINDING WHEEL FOR PAPER PULP.

Application filed January 17, 1925. Serial No. 3,107.

This invention relates to grinding wheels, more particularly wheels for grinding wood in the manufacture of paper pulp.

Briefly, my improved wheel consists of a shaft on which is mounted a series of metal spiders or disks. A plurality of segmental blocks of abrasive material, forming rings, are mounted on these disks, the inner edges of the segments being confined between the disks and secured there by pressing the terminal disks toward each other. Other rings, also composed of segments, are placed between and interlocked with the first mentioned rings.

15 Grinding wheels in which the abrasive element consists of a plurality of rings are not new, nor is it new to build up such rings with segmental blocks of abrasive material. My invention resides in certain novel structural features, the advantages of which will be apparent when my improved wheel has been described. I shall therefore proceed to describe it, referring to the accompanying drawing, in which,

25 Fig. 1 is a side elevation of the wheel in its completed state;

Fig. 2 is a sectional view, and

Fig. 3 is an end view of my improved wheel.

30 Mounted on a shaft 10 are two metal disks 11. Between these disks on the shaft are disks or spiders 12. All of these disks 11 and 12, are secured to the shaft with splines 13, by which the disks are positively rotated 35 when the shaft rotates, but all are free to move longitudinally on the shaft. The shaft is threaded at 14—14, to receive nuts 15, whereby the disks 11—11 may be moved toward each other for a purpose hereinafter referred to.

40 Rings composed of segmental blocks 16, of abrasive material, are carried by the disks 11 and 12, the inner edges of the blocks being confined between the disks and securely held there by pressure imparted by screwing up the nuts 15. The portions of the blocks confined between the disks are dove-tail shaped in cross section, this being shown at 17 in Fig. 2, and the portions of the disks which 45 confine the dove-tails have a shape comple-

mentary to the dove-tail. The portions of the blocks 16 outside of the disks are wedge shaped in cross section, the thicker portion being at the outer part of the ring. The disks 12 are approximately as thick as the blocks 16 at their thinner parts, which causes the formation of spaces between adjacent rings. Because of the blocks becoming gradually thicker toward their peripheries these spaces become gradually broader from the periphery of the wheel inward. Within these annular spaces I place other rings, also composed of segmental blocks of abrasive material, these being indicated at 18 in Fig. 2. In cross section the segments 18 are also 55 wedge shaped, but the thicker part is nearest the shaft, the reverse of segments 16. Thus the segments 18 are, in effect, interlocked with the segments 16. As the segments 16 are securely anchored to the disks by means 60 of the dove-tails all of the segments, both 16 and 18, are enabled to resist the effect of centrifugal force, as well as other forces tending to dislodge them. In order to give the outer rows of segments greater stability the disks 65 11 are slightly larger in diameter than the disks 12. As shown in Fig. 1 the longitudinal joints between the segments are offset.

70 It is not essential that the rings be made up of segments; solid rings may be used. The 75 advantage of using segments is that they are easier to make. If desired some other manner of interlocking the segments 16 and 18 may be used. Moreover, the intermediate rings may be dispensed with, together with 80 the spaces in which they are lodged. The segments 16 may be broadened and arranged to overlie half the thickness of the disks 12 by which they are supported, thus bringing 85 neighboring segments together. If the rings 90 be made in this way the disks 12 may be made thinner so as to reduce the width of the overlying parts of the segments. This is so obvious that it is deemed unnecessary to illustrate this suggested modification.

95 As the disks are free to move on the shaft, screwing the nuts 15 tight clamps all of the rings with substantially equal pressure. The hubs on the disks are spaced apart, and there is nothing to prevent the disks moving 100

longitudinally and accommodating themselves to this tightening arrangement. Drawing the nuts tight flexes the disks 11 slightly, resulting in the segments being gripped between the disks by a resilient pressure. While the clamping arrangement shown is quite sufficient for the purpose, and capable of holding the segments firmly in place, if desired a little cement of some kind may be poured 10 into the crevices. This may be desirable as a means of excluding water from the interior of the wheel. Melted sulphur makes a good cement for this purpose. While I have shown a wheel with four main and three secondary rings, the number of rings may be increased or decreased if desired. In fact two disks 11 and one disk 12 may be used, with only three rings.

What I claim as my invention is as follows:

20. 1. In a grinding wheel, a series of disks mounted on a shaft, abrasive rings whose inner edges are confined between the peripheral portions of said disks, said disks being arranged for relative longitudinal movement on 25 the shaft, whereby relative longitudinal movement of approach between the terminal disks in the series will cause said confined portions of the rings to be gripped between the disks, the unconfined portions of the rings being of 30 such thickness that spaces are left between them, which spaces are occupied by additional rings, and means for drawing said terminal disks together to grip said inner edges, said means acting at a substantial distance within 35 the inner edges, because of which the pressure exerted on the rings by the disks is due to the resiliency of the terminal disks.

2. In a grinding wheel, a shaft, three or 40 more disks carried thereby and free to slide longitudinally thereon, abrasive rings supported thereby, the inner edges of said rings being confined between said disks, one ring between each two disks, said rings being held 45 against the action of centrifugal force by a dove-tail connection to the disks, and additional rings between the aforesaid rings, the portions of the first mentioned rings outside 50 of the disks being wedge-shape in cross section with the peripheral portion the thickest, the cross section of the intervening rings being 55 complementary, thereby filling the spaces between the first mentioned rings.

3. In a grinding wheel, a shaft, three or 60 more disks carried thereby and free to slide longitudinally thereon, abrasive rings supported thereby, the inner edges of said rings being confined between said disks, one ring between each two disks, said rings being held 65 against the action of centrifugal force by a dove-tail connection to the disks, and additional rings between the aforesaid rings, the portions of the first mentioned rings outside 70 of the disks being wedge-shape in cross section with the peripheral portion the thickest, the cross section of the intervening rings be-

ing complementary, thereby filling the spaces between the first mentioned rings, said rings being composed of segments of equal degree, the inter-segmental joints of the last mentioned rings being placed intermediate the 70 joints of the first mentioned rings.

EDWARD ANDERSON.
